UNITED STATES PATENT OFFICE

167,498

POCKET PRUNING KNIFE

George Dalianis, Wappingers Falls, N. Y.

Application March 21, 1952, Serial No. 18,996

Term of patent 14 years

(Cl. D22—3)

To all whom it may concern:

Be it known that I, George Dalianis, a citizen of the United States, residing at Wappingers Falls, in the county of Dutchess and State of New York, have invented a new, original, and ornamental Design for a Pocket Pruning Knife, of which the following is a specification, reference being had to the accompanying drawings, forming a part thereof.

Figure 1 is a side view of a pocket pruning knife, showing my new design, with the blade of the knife extended for use;

Figure 2 is a view showing the knife rotated 90° about its horizontal axis;

Figure 3 is a side view showing the blade folded back upon the handle.

I claim:

The ornamental design for a pocket pruning knife, as shown and described.

GEORGE DALIANIS.
